(57) CLAIM

The ornamental design for an insert for suitcase, as shown and described.

DESCRIPTION

FIG. 1 is a perspective view of the insert for suitcase showing my new design;

FIG. 2 is a front view thereof;

FIG. 3 is a rear view thereof; and,

FIG. 4 is a side view thereof.

The broken lines illustrate portions of the insert for suitcase and form no part of the claimed design.

1 Claim, 3 Drawing Sheets

FIG. 1

FIG. 4
